(57) **CLAIM**

The ornamental design for a hose connector sleeve as shown and described.

DESCRIPTION

FIG. 1 is a perspective view of the front, top, and right side of a hose connector sleeve;

FIG. 2 is a perspective view of the front, top, and left side thereof;

FIG. 3 is a front view thereof;

FIG. 4 is a top view thereof;

FIG. 5 is a bottom view thereof;

FIG. 6 is a right side view thereof;

FIG. 7 is a left side view thereof;

FIG. 8 is a cross-sectional view thereof taken along section line 8-8 of FIG. 4;

FIG. 9 is a plan view thereof, shown in a state of use;

FIG. 10 is a cross-sectional view thereof taken along section line 10-10 of FIG. 9; and,

FIG. 11 is a cross-sectional view thereof taken along section line 10-10 of FIG. 9 shown in a state with the hose connector sleeve pushed in.

A rear view of the hose connector sleeve is omitted because the rear view is symmetrical to the front view.

The broken lines in the figures indicate portions of the hose connector sleeve that form no part of the claimed design.
